CLAIM

The ornamental design for a lamp, as shown and described.

DESCRIPTION

FIG. 1 is a front and top perspective view of a lamp, showing my new design;

FIG. 2 is a rear and top perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a perspective view thereof, showing the lamp in a flipped position;

FIG. 10 is an enlarged detail view of area with a indicator "10" in FIG. 1;

FIG. 11 is an enlarged detail view of area with a indicator "11" in FIG. 2;

FIG. 12 is an enlarged detail view of area with a indicator "12" in FIG. 3; and,

FIG. 13 is an enlarged detail view of area with a indicator "13" in FIG. 9.

The broken lines in the figures illustrate portions of the article that form no part of the claimed design. The dot dash dot broken lines in FIGS. 1-3 and 9-13 depict the boundaries of the enlarged detail areas and form no part of the claimed design.

1 Claim, 13 Drawing Sheets
